UNITED STATES PATENT OFFICE.

JAMES BARKER, OF DETROIT, MICHIGAN.

FLEXIBLE-HINGE LEAF.

1,103,911.

Specification of Letters Patent. Patented July 14, 1914.

Application filed July 15, 1911. Serial No. 638,741.

To all whom it may concern:

Be it known that I, JAMES BARKER, a citizen of the United States of America, residing at Detroit, in the county of Wayne 5 and State of Michigan, have invented certain new and useful Improvements in Flexible-Hinge Leaves, of which the following is a specification, reference being had therein to the accompanying drawings.

10 The invention relates to leaves more particularly designed for use in connection with loose-leaf ledgers, and the invention consists in the peculiar construction of the hinge section for the leaf as hereinafter set forth.

In the drawings.—Figure 1 is a perspective view of the leaf; Fig. 2 is an enlarged diagrammatic sectional view illustrating the hinge section.

20 In the present state of the art, leaves for ledgers have been constructed in which a flexible hinge section is formed by thinning a portion of the paper stock, thereby increasing the flexibility.

25 The present invention relates to a construction in which flexibility is obtained without any thinning or reduction in the paper stock, but which at the flexing point is of a softer nature. Such a construction is 30 preferably obtained by treating the material with a softening compound which renders it less resilient and more flexible.

In the specific process which is preferably employed for forming the hinge section, the paper stock is treated with a softening solution for which the following formula is suitable:

Wood alcohol ----- 5 to 7 ounces.
Oxalic acid ----- 1 ounce.
40 Glycerin ----- $\frac{1}{2}$ ounce.

The solution may be applied by any suitable implement such as a brush being applied to the surface of the leaf and confined 45 to the area of the section which is to be rendered flexible. After the solution has

penetrated the fibers the surplus material is wiped off and the sheet dried. The result of the treatment is that the section to which the liquid is applied is rendered flexible and forms a suitable hinge.

In the drawings, A represents a leaf such as a loose-leaf ledger leaf, and the shaded strip indicated at B represents the section which has been treated. In Fig. 2 this is 55 diagrammatically illustrated by representing the section B of a different texture than that of the body of the leaf.

While I have described a specific compound for use in my process it is obvious 60 that there may be many equivalents for producing the same effect. The particular process for obtaining the product does not form any portion of the present invention but will be the subject matter of a distinct application for patent.

What I claim as my invention is:

1. A book leaf formed of paper having a hinge portion, comprising a narrow section integral with the body of the leaf impregnated with a softening material, increasing 70 the flexibility of the hinge portion over that of the body of the leaf.

2. A book leaf formed of paper having a hinge portion, comprising a narrow section 75 integral with the body of the leaf of uniform thickness with the body, said section being impregnated with a softening material, increasing the flexibility thereof over that of the body of the leaf.

3. A book leaf formed of paper of uniform stock throughout and having a narrow section integral with the body of the leaf, treated with a softening material increasing the flexibility of said section over 85 that of the body of the leaf.

In testimony whereof I affix my signature in presence of two witnesses.

JAMES BARKER.
